UNITED STATES PATENT OFFICE.

HORACE H. CLARK, OF OAK PARK, ILLINOIS.

GAS BURNER.

Application filed June 8, 1922. Serial No. 586,698.

To all whom it may concern:

Be it known that I, HORACE H. CLARK, a citizen of the United States, residing at Oak Park, in the county of Cook and State of Illinois, have invented certain new and useful Improvements in Gas Burners, of which the following is a specification.

This invention relates to burners for gaseous fuel and has for its object to provide a burner for use in developing heat through combustion of explosive gaseous fuel, or fuel in which the oxidizing medium has been mingled with the combustible element before it reaches the burner. In igniting gaseous fuel of this kind considerable difficulty has been experienced in preventing, on the one hand back firing, and on the other hand extinguishment of the flame due to internal furnace atmosphere disturbance or excessive velocity in the issuing mixture, at irregular intervals. Difficulties have also been encountered in providing a burner construction that would withstand the high temperature developed in the successful combustion of the pre-conditioned fuel referred to.

Now the present invention proceeds upon the principle of partially arresting the fuel mixture in the burner, subdividing it into a plurality of jets, and issuing these jets under ample velocity to prevent back firing and at the same time under conditions that will induce complete ignition, and insure against isolation of flame from the burner and consequent extinguishment.

In carrying out the invention, the burner formed preferably with an expansion chamber in addition to the fuel conduit, is fitted with a mouth piece preferably of refractory material protruding beyond the metal of the burner, made substantially cylindrical cup-shape having a bottom that constitutes an arresting wall for the fuel mixture in the expansion chamber, with its cylindrical wall upstanding from the bottom to develop an open ended ignition chamber, and with perforations in the bottom that permit the fuel mixture to issue in sub-divided jets into the ignition chamber, and with some of the perforations inclined to the axis of the burner and directing their jets into impingement

with the said upstanding wall in a manner to set up eddy currents and spread the ignition throughout the ignition chamber before the burning gases can pass the same; the inclined perforations having a diameter corresponding substantially to that of the other perforations so that they carry substantially fractions of the fuel body and interfere with the direct blast of fuel through the ignition chamber to an extent that insures retention of combustion therein.

In the accompanying drawings—

Figure 1 is an elevational view partly in section, of a portion of a gaseous mixture manifold, with burners mounted thereon, and means for delivering gas and combustion supporting air thereto;

Figure 2 is a vertical axial section of a burner of relatively small capacity;

Figure 3 is a top plan view of the burner tip shown in Figure 2;

Figure 4 is a top plan view of a burner tip of relatively large capacity, with a somewhat different arrangement of fuel ports; and;

Figure 5 is an axial section of the burner tip, shown in Figure 4.

1 represents a portion of a fuel mixture manifold having mounted thereon burners 2, and having connected therewith a gaseous or other fluid fuel pipe 3 and an air supply pipe 4. The air supplied through pipe 4 is assumed to be under such pressure, and the two pipes 3 and 4 assume such relation to the manifold 1, and to each other, that a thorough mingling of the fuel and oxidizing medium results, the mixture flows through the manifold and out through the burners at a rate that exceeds the rate of flame propagation through the mixture, when ignited, and back firing is prevented.

For the sake of inducing better combustion of the mixture and insuring against extinguishment by detachment of the flame from the burners, under disturbances of furnace atmosphere, each burner 2 is constructed with an expansion chamber 2^a, in addition to its fuel conduit 2^b, and is fitted with a deep cup-shaped or crater-like mouthpiece 5 that develops in the burner an ignition chamber 5^a. Mouthpieces 5 store heat

to a degree above the flashing point of the mixture and thereby insure ignition of the mixture. It has an inner transverse wall that forms a bottom to this ignition chamber and is provided with a circumferential series of bores such as shown at 6 and 6^a, so that it constitutes a perforated wall across the main channel of the burner, that constricts and subdivides the flow of mixture reaching such ignition chamber, and thereby guards against extinguishment or impaired ignition that might otherwise result from sudden expulsion of an excessive volume of cool mixture, under irregularities in the air feed. Moreover, in order to further guard against escape of the issuing mixture before thorough ignition can take place, some of the ports preferably those in the outer series in mouthpieces of large dimensions, or certain of them in said outer series, for instance, the alternate ports in mouthpieces of smaller dimensions, are inclined to the axis of the burner in a manner to cause the jets issuing therefrom to impinge against and be deflected from the upstanding cylindrical side wall of the ignition chamber, and thereby set up eddy-currents in the ignition chamber and within the volume of issuing mixtures. The inclined perforations are of substantially the same diameter as the straight perforations so that they carry substantial fractions of the volume of fuel delivered as distinguished from mere pilot jets; and thus the impinging fuel streams maintain the refractory material of which the mouthpiece is formed, at a temperature that is above the flash point of the fuel mixture and thereby insure re-ignition in case the flame should be wholly extinguished by any unusual condition.

Ignition within a chamber 5^a such as that herein disclosed, of a mixture of gaseous fuel and oxidizing medium previously mingled in proper proportions, generates a flame that is rapidly destructive of most metals that are economically available for making burners of the kind herein required; for that reason, the mouthpieces 5 are preferably constructed of lava or other highly refractory material, and assembled with the burners, preferably through the medium of screw threads, and with sufficient protrusion beyond the metal body of the burner to prevent flame impingement upon the latter.

I have discovered that when a cup-shaped tip or mouthpiece of this kind is made of such refractory material it maintains the proper functioning of the burner, because if iron is used, which quickly deteriorates under the action of the heat, the shape of the cup, and particularly the depth of its cylindrical wall, becomes so impaired that separation of the flame from the burner and consequent extinguishment occurs within a short time after the burner is put into use, and thus necessitates constant replacement. A cup-shaped tip made of lava or other refractory material withstands the action of the heat indefinitely and maintains with accuracy the lines and proportions of the burner that are so important to its successful action. Furthermore, since lava or equivalent refractory material has a very low coefficient of heat conductivity, the use of such material in a cup-shaped tip or mouth piece, such as herein shown, has the advantage of promoting ignition notwithstanding the impingement of the fuel mixture against the cylindrical wall; in other words it permits this impingement and consequent control of the gases hereinabove described without serious loss of efficiency due to cooling which would result from the use of a metal mouth piece. Again, by the use of a refractory material for a cup-shaped mouth piece in which the mixture of fuel with oxidizing agent impinges against the surrounding wall, oxidation, which would be particularly destructive to metal at the high temperatures incident to the operation, is wholly avoided.

I claim:

1. A mouthpiece for gaseous fuel burners comprising a side wall adapted to fit an opening in a fuel supply member and a transverse bottom wall forming with said side wall an open cup-shaped ignition chamber; said bottom wall extending entirely across said ignition chamber and in position to form a fuel controlling confine of the supply member when the mouthpiece is applied; said bottom wall being formed with perforations admitting fuel in subdivided streams to said ignition chamber; said perforations being positioned to deliver said streams in the general longitudinal direction of the side wall, but some of them being inclined toward and causing their streams to impinge against said side wall; and the perforations so inclined substantially corresponding in bore to the other perforations and producing eddy currents which break up the direct blast of the fuel through the ignition chamber and retain combustion within the latter.
2. A burner for gaseous fuel comprising a shell formed to provide an expansion chamber, and having an opening to admit fuel and an opening to receive a mouthpiece, and a mouthpiece comprising a substantially cylindrical wall fitting the opening of the shell and a transverse bottom wall integral with said cylindrical wall and extending entirely across the same in position to provide a confine for the shell opening; said transverse wall being constructed with perforations all extending in the general direction of the axis of the cylindrical wall; said transverse wall and cylindrical wall forming an ignition chamber into which fuel enters through

said perforations from said expansion chamber; some of said perforations being directed to cause fuel streams to impinge against the cylindrical wall and having a capacity corresponding substantially to the capacity of the other perforations and being sufficient in number to carry a large fraction of the fuel body delivered and produce eddy currents which break up the direct blast of fuel through the ignition chamber and retain combustion therein. 10

Signed at Chicago, Illinois, this 2nd day of June, 1922.

HORACE H. CLARK.
